UNITED STATES PATENT OFFICE.

GREENE C. HOSCH, OF ST. LOUIS, MISSOURI, ASSIGNOR TO THE MEASUREGRAPH COMPANY, OF ST. LOUIS, MISSOURI, A CORPORATION.

FABRIC-CUTTING DEVICE.

1,343,722.

Specification of Letters Patent. Patented June 15, 1920.

Application filed February 10, 1919. Serial No. 275,978.

To all whom it may concern:

Be it known that I, GREENE C. HOSCH, a citizen of the United States, residing in the city of St. Louis, and State of Missouri, have invented new and useful Improvements in Fabric-Cutting Devices, of which the following is a specification.

This invention relates to a novel device for use in severing a measured portion of fabric, and particularly of fabric that is of considerable width, such, for example, as ordinary dress goods.

The character of material with which my device is designed to be used is usually disposed in the form of bolts, and when a given length has been measured therefrom the operator cuts off the measured portion with a pair of scissors. Not only is this process of severing the goods slow, but it is unreliable, as it is difficult, if not impossible, to cut the goods on a straight line; and to be on the safe side, the clerk usually errs, both in starting the cut and finishing, in favor of the customer. As a result, there is considerable material given to the customer for which the shopkeeper receives no pay, and in the case of a large establishment this amounts to a great deal in the course of a day, especially with high priced goods, such as silks. Further, it very frequently happens that in cutting the material actually sold, the scissors will engage other material lying on the counter, or other portions of the material sold, in either case cutting such material and spoiling it.

It is the design of my invention to provide means for severing goods accurately and rapidly and on a straight line and at the same time to avoid the danger of cutting other material, or other portions of the same material as that being cut, in the cutting operation.

With these objects in view the invention comprises, in its preferred embodiment, a relatively long member, that is to say, a member as long as, or longer than, the material to be severed is wide, such member providing a slide for a cutting device movable thereover from end to end and having a handle at one end and a gripping device located adjacent thereto and operable manually to hold the cloth at one edge portion as it is being cut.

The invention is illustrated in the accompanying drawing, in which:

Figure 1 is a top plan view of my device;

Fig. 2 is a side elevation thereof;

Fig. 3 is a view on an enlarged scale partly in section and partly in side elevation, the view being broken away in a manner to decrease the actual length of the device;

Fig. 4 is a sectional view through the frame or carriage of the cutting device, a part of the latter being broken away to better illustrate the construction;

Fig. 5 is a central vertical sectional view taken through the cutting device;

Fig. 6 is a cross-sectional view on the same scale as Fig. 3 illustrating the manner of securing certain supports on the device, the view being substantially a section on line 6-6 of Fig. 1, with certain parts omitted; and

Fig. 7 is a cross-sectional view on the line 7-7 of Fig. 1.

Referring now to the drawing, the numerals 1, 2, indicate two parallel members, in the form of rails, or bars, which are secured at their rear ends to a handle 3 by means of side plates 4, 5, the handle being provided with a central, flat, forwardly-projecting plate 6, which serves to space the bars 1 and 2 the necessary distance apart and to hold them in such spaced relation. At their outer ends the bars are maintained in separated relation by a spacing block 7 carried by a cap 8 fitted over the ends of said bars and secured thereon by screws 9. Pins 10 are shown as securing the spacing block 7 in the cap 8, but this block could be soldered thereon or cast integral with the cap, or in fact, be secured in any suitable manner therein. A rubber, or other, button 11 is secured on the under side of said cap 8 by means of a countersunk screw 12. At intervals throughout their length, the bars 1 and 2 are embraced by yoke members 13, which are countersunk in the sides of the bars and secured thereon by means of screws 14, the yoke members 13 projecting below the bottom edges of said bars to permit of the free movement of the cutting device as later described, and also to brace the bars and help to preserve their parallel relation. between the plates 4 and 5 and the bars 1 and 2 by means of screws 15 are angle bars 16 which have secured on their lower bent ends buttons 17 which project below the bottom edge of the bar lower than the button 11 or the yoke members 13, so that when the device as a whole is in position on the counter its rear end will be slightly raised as compared with its forward end, thus 10 maintaining the yoke members 13 out of contact with the counter when the device is in use. Pivotaly mounted at 18 in the side plates 4, 5, and spacing plates 6 are two gripping arms, 18, 19, respectively, having right 15 angular extensions 20 to provide broad bearing surfaces at their outer ends; each of the bars 18, 19 is in the form of a bell crank lever which works in a space between the respective plates 4, 5, and the respective bars 20 1, 2, and passing beneath said bars are united to form, or are otherwise connected to, a common trigger 21, which is adapted by means of a bridge piece 22, to work against a spring 23 secured at its ends in notches, or 25 otherwise, on the under side of the handle portion of the device, as shown in Fig. 3. When the goods are placed under the ends of the arms 18, 19 and the trigger 21 pulled the gripping surfaces 20 will be caused to 30 engage the fabric and hold it from being moved in the cutting operation. The numeral 24 indicates a semi-circular housing, which also constitutes a carriage for the cutting device, secured within which are two 35 circular shaped metal plates 25 and 26, which are cut away below the lower edge of the housing 24 to form a curved mouth 27 for the entrance of the goods to be cut. The plates 25 and 26 are secured in position by 40 means of screws 28 passing from side to side of the housing 24, and secured by means of studs 29 and screws 29^a between said plates is a cutter 30, so positioned as to present an inclined cutting edge 31 extending across the 45 mouth 27. On the bottom sides of the plates 25 and 26 are projecting pieces 32 which are bent outwardly as indicated at 33 (Fig. 5), which serves as a stop to prevent the withdrawal of the cutting device from between 50 the bars 1 and 2. These projections in the movement of the carriage 24 over the bars pass through the yoke members 13, which, as 55 previously stated, project below the bar a sufficient distance for this purpose. At opposite ends of the device I insert between 60 said bars a suitable strip of a relatively soft material, such as leather, felt, or the like, indicated by the numerals 34 (Fig. 3), which serve as cushions for the impact of the cutting device at the limits of its movement in either direction and also to deaden the noise of such impact.

In operation, the operator, having measured a length of material from the bolt, will 65 insert the bars 1 and 2 under the material

and extend it across the counter until its other end passes to or beyond the opposite side of the material. In such operation the end of the material toward the operator will pass under the gripping arms 18 and 19, or 70 it may be placed thereunder by the operator. He will then grasp the handle 3 and with one finger pull the trigger 21 to bring the gripping edges 20 down upon the material. The operation is similar to that involved in 75 grasping the handle and pulling the trigger of a pistol, and the handle 3 and trigger 21 are shaped and relatively positioned to afford the greatest ease in this operation. It should be stated that in positioning the material beneath the gripping arms 18 and 19 the carriage 24 is lifted so that the edge of the goods may pass into the mouth 27, the stops 33 being positioned sufficiently below the lower edge of the bar to permit the carriage 24 to be raised for this purpose. While holding the gripping arms depressed to firmly engage the material, the operator next grasps the housing or carriage 24 and moves the same rapidly outward over the bars 1 and 2 the desired distance to cut the material across its entire width, the cutting edge 31 of the blade engaging the material slantwise and making a sheering cut. In practice I have used a razor blade of a well 85 known make as the cutter 30.

It will readily be seen that the length of the device when passed entirely under the material to be cut enables the operator to gage by his eye a line more truly at right 100 angles to the length of the goods than would be the case when he attempts to cut across the material without any guide, by means of scissors.

It will be obvious that various changes 105 can be made in the details of construction of my device without departing from the principle of the invention. For example, the supporting part of the device comprising the parallel members 1 and 2 could be a unitary 110 structure instead of being constructed of two separate bars, the space between the two members 1 and 2 being cut out, or formed by casting, or otherwise. For the sake of brevity I have referred to this part of the 115 device in certain of the claims as a bar.

I claim:

1. A device for severing fabric comprising a pair of rails, a gripping device for the fabric pivotally mounted near one end of 120 said rails and terminating short of the other end, and a cutting device mounted to slide over said rails, and beyond said gripping device.

2. A device for severing fabric comprising a bar having a longitudinal slot, a gripping device for the fabric located at one end of the bar and a cutting device slideable in said slot and beyond said gripping device. 125

3. A device for severing fabric comprising 130

ing a bar having a longitudinal slot, a gripping device for the fabric pivotally mounted at one end of the bar and terminating short of the other end, and a cutting device 5 slideable in said slot and beyond said gripping device.

4. A portable device for severing fabric comprising a bar having a longitudinal slot, a hand-grasp provided at one end of the 10 bar, a spring controlled gripping device for the fabric pivotally mounted adjacent to said handle and provided with a trigger for depressing it against the resistance of the spring, and a cutting device slideable in said 15 slot.

5. A portable device for severing fabric comprising a bar insertible under the fabric and having a longitudinal slot, a gripping device for the fabric located at one end of 20 the bar and a carriage mounted to slide on said bar beyond said gripping device on said bar and carrying a blade working in said slot.

6. A portable device for severing fabric 25 comprising a bar insertible under the fabric and having a longitudinal slot, a gripping device for the fabric located at one end of the bar and a carriage mounted to slide over said bar and of a length to grip the 30 edge portion only of the fabric to be cut and having a limited vertical movement relative thereto, and a blade mounted in said carriage and working in said slot.

7. A portable device for severing fabric 35 comprising a bar insertible under the fabric and having a longitudinal slot, a gripping device for the fabric located at one end of the bar, a carriage slidably mounted on said bar, a frame mounted in said carriage 40 and extended through said slot, retaining devices located on said frame at a distance from the lower edge of said bar and a blade

carried by said frame and working in said slot.

8. A portable device for severing fabric 45 comprising a bar insertible under the fabric and having a longitudinal slot, a gripping device for the fabric located at one end of the bar, a carriage mounted to slide over 50 said bar and having a member projecting through said slot and retained therein and provided with a recess for the entrance of the fabric to be cut, and a blade mounted in said carriage to extend into said slot and across said recess. 55

9. A device according to claim 8 in which the bar is embraced at intervals by yoke members secured to the bar and projecting below the bottom thereof.

10. A portable device for severing fabric 60 adapted to be supported upon a table comprising a bar insertible under the fabric and having a longitudinal slot, a gripping device for the fabric located at one end of the bar, a cutting device slideable in said 65 slot, and supports carried by said bar and projecting below the lower side thereof to maintain the same in an elevated position above the table.

11. A device for severing fabric comprising 70 a bar having a longitudinal slot, a gripping device for the fabric located at one end of the bar, and having its gripping portion normally held above the surface of the bar to provide a space for the insertion of 75 the edge portion of the fabric to be cut, means for depressing said gripping device to engage the inserted fabric, and a cutting device slideable in said slot and beyond said gripping device. 80

In testimony whereof, I have hereunto set my hand.

GREENE C. HOSCH.
